DETONATING TOY

Filed March 31, 1930

Theodore J. Deck, Sr.
INVENTOR

BY *Victor J. Evans*

ATTORNEY

UNITED STATES PATENT OFFICE

THEODORE J. DECK, SR., OF BALTIMORE, MARYLAND

DETONATING TOY

Application filed March 31, 1930. Serial No. 440,559.

This invention relates to a detonating toy, the general object of the invention being to provide a toy which can be thrown against a wall or the like so as to cause a cap carried by the toy to explode or the device can be thrown into the air, where it will be so controlled by means forming a part thereof that it will strike a pavement or the like when it returns to earth, so that the cap will be exploded.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:—

Figure 1 is an elevation of the device.

Figure 2 is a top plan view thereof.

Figure 3 is a section on line 3—3 of Figure 1.

Figure 4 is a view similar to Figure 3, but showing a modification.

Figure 5 is a view showing another modification.

In these views, the numeral 1 indicates the body of the device which is of substantially circular shape in cross section and of elongated form, with its rear end formed with the wings 2. The forward end of the body is of convex shape, as shown at 3, and the body is provided with a bore 4 which passes longitudinally through the body to receive the stem 5 of a head 6, the head being rounded as shown, and having a convex rear face to conform to the concaved end of the body. A cap 7 is threaded to the rear end of the stem and a spring 8 is placed on the rear part of the stem and is located in a socket 9 formed in the rear part of the body and through which the stem passes. A part of the cap fits in the socket and the spring, bearing against the forward end of the socket and the cap, acts to hold the head against the forward end of the body. A perforated flat part

10 is formed on the outer end of the cap to receive ribbons 11 or the like.

Thus the wings 2 and the ribbons cause the body to travel with the head 6 foremost when the device is thrown into the air, and by placing caps 12 or the like between the head and the forward end of the body, said caps will be exploded when the head strikes a wall or other surface. By exerting pressure on the cap 7, the head is moved away from the forward end of the body so that the caps can be placed between the parts and when, when the pressure is released, the spring will draw the head against the caps and thus hold them in place.

In the modification shown in Figure 4, the forward end of the body is formed with a concavity 3' and the head 6' is of spherical shape so that a part thereof will fit in the concavity. Thus the caps are placed between the head and the wall of the concavity when pressure is exerted upon the stem or the cap carried thereby, so that the detonating caps can be placed between the spherical head and the forward end of the body. As before stated, when the device is thrown into space, it will travel along with the head foremost so that when the head strikes a wall or other object, the blow will explode the caps placed between the head and the forward end of the body. If the device is thrown upwardly into the air, it will reverse itself after losing its momentum and drop head foremost against a pavement or the like and explode the caps.

Figure 5 shows the body formed with a conical recess 3'' and the head 6'' has a conical upper part to fit in the recess and a semi-spherical lower part. In other respects, this form of the invention is the same as that before described.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A detonating toy comprising an elongated

- body and having a bore extending there-through from one end to the opposite end and a portion of said bore enlarged to provide a chamber and a shoulder within the body, a stem slidable in the bore and extending beyond the ends of the body, a head on one end of the stem to co-operate with one end of the body in exploding a cap when brought against an object, tapering wings
5 at the other end of the body, a member detachably and adjustably secured to the stem and partially received within the chamber, a spring between said member and shoulder to normally urge the head toward the respective end of the body, a flattened portion formed on the member and having an elongated eye, and a plurality of flexible strips secured to the eye to co-operate with the wings in causing the head to strike an object when the body is thrown through the air toward said object.

In testimony whereof I affix my signature.
THEODORE J. DECK, Sr.
